US00D754676S

(12) United States Design Patent
Vazquez et al.

(10) Patent No.: US D754,676 S
(45) Date of Patent: * Apr. 26, 2016

(54) DISPLAY SCREEN OR PORTION THEREOF
 WITH GRAPHICAL USER INTERFACE

(71) Applicant: ADP, LLC, Roseland, NJ (US)

(72) Inventors: Serafin Vazquez, Cortlandt Manor, NY (US); Carl Collins, Brooklyn, NY (US); Anna Carsen, New York, NY (US); Keith Fulton, South Orange, NJ (US)

(73) Assignee: ADP, LLC, Roseland, NJ (US)

() Term: 14 Years

(21) Appl. No.: 29/487,140

(22) Filed: Apr. 4, 2014

(51) LOC (10) Cl. 14-04

(52) U.S. Cl.

USPC D14/485

(58) Field of Classification Search

USPC D14/485-488

(57) CLAIM

The ornamental design for a display screen or portion thereof with graphical user interface, as shown and described.

DESCRIPTION

The sole FIGURE is a front view of a display screen or portion thereof with graphical user interface showing a new design. The outermost box in broken lines in the Figure illustrates the perimeters of a display screen or portion thereof and forms no part of the claimed design.

Subject matters in broken lines in the Figure, such as text boxes, texts, words, letters, symbols, icons, numbers, images, and/or lines, form no part of the claimed design.

1 Claim, 1 Drawing Sheet
